UNITED STATES PATENT OFFICE.

RICHARD M. SMYTHE, OF BROOKLYN, NEW YORK.

COMB.

Application filed August 21, 1923. Serial No. 658,537.

To all whom it may concern:

Be it known that I, RICHARD M. SMYTHE, a citizen of the United States, residing at Brooklyn, in the county of Kings and State 5 of New York, have invented certain new and useful Improvements in Combs, of which the following is a full, clear, and exact description.

The present invention relates to combs, 10 and has for its object to provide such an article with teeth having grooves in the side walls thereof for the collection of dandruff, dust, germs and the like from the hair and scalp of the user.

15 A further object of the invention resides in combining with such a comb a means for imparting a suction along the grooves of the comb teeth for the purpose of removing the dandruff, etc., therefrom as soon as 20 collected.

Another object of the invention resides in the provision of a simple and inexpensive means for mounting the comb in operative relation to the suction-producing means.

25 Other objects and advantages of the invention will be apparent from the following description when taken in connection with the accompanying drawings, in which:

Figure 1 is a side elevation of the 30 complete device.

Figure 2 is an enlarged sectional view taken on line 2—2 of Figure 1.

Figure 3 is an enlarged fragmentary sectional view of the mounting for the comb.

35 Figure 4 is a perspective view of the comb and holder detached, and

Figure 5 is a side elevation, partly broken away, of a comb and attachment adapted to be connected to any type of vacuum sweeper.

40 It is generally well known that the hair and scalp of the human head is often insanitary, not only because of the formation of dandruff, but also because of the collection of dust, dirt, bacteria and the like 45 from the air. This foreign matter cannot

ordinarily be removed by a brush or comb, for the reason that any such matter which may be collected at one stroke of the comb is immediately put back into the hair at 50 the next stroke. Furthermore, the hair and scalps of women are even more difficult to clean, even by shampooing, due to the great length and quantity of hair.

It is for the purpose of overcoming the

foregoing difficulties that I have devised 55 the present construction in which the comb 1 is provided with grooves 2 extending longitudinally of the side walls of the teeth 3. Each of these grooves extends from a point adjacent the free end of the tooth to 60 the back of the comb, as more clearly indicated in Figures 2 and 3 of the drawings. With a comb of this construction it will be apparent that dandruff, etc., will be collected in the grooves 2 as the comb is drawn 65 through the hair, and may be wiped therefrom from time to time as desired.

A comb provided with grooves as described will aid greatly in cleaning the hair. I have found, however, that by applying 70 a suction to the grooves 2 the scalp and hair may be thoroughly cleaned by merely running the comb therethrough in the usual manner. To this end I have provided a

75 tube 4 of metal or other similar material formed with a longitudinal slot 5 extending from one end of the tube to a point slightly beyond the middle thereof. The tubular holder 4 is formed along the opposite edges of the slot 5 with outwardly extending parallel flanges, as shown in Fig. 2, which engage the opposite faces of the comb and afford broad bearing surfaces therefor, and these flanges contribute 80 greatly to the firm securing of the comb within the holder and efficiently take the lateral pressure exerted against the comb when the latter is drawn through the hair.

85 The grooves 2 are at the front and back faces of the comb and are open at the upper edge of the back of the comb, and when the comb is in position in the holder the upper edge of the comb is free of the walls thereof, thereby leaving the upper ends of the grooves 2 unobstructed. The 90 teeth and grooves 2 are tapered downwardly, and said grooves by extending through the back of the comb and being wider at their upper ends may be readily cleaned out. The comb 1 is positioned in 95 the slot 5 with one of its notches 6 engaged by the bridge piece 7 of the tube, while the opposite notch 6 is engaged by a flange 8 of the cap 9 fitting over the end of the tube.

100 To the opposite end of the tube may be fitted a casing 10 inclosing a well known type of air pump and having a receptacle 11 of twill fabric, metal or glass detachably

connected thereto. A handle 12 is provided on the tube 4 for the purpose of manipulating the apparatus, while an electric connection 13 is provided for connecting the 5 device to the usual wall plug or the like.

The apparatus shown in Figure 1 is complete in itself and may be used in barber shops, hair dressing parlors or in the home. In Figure 5, however, is shown the identi- 10 cal device with the air pump omitted. In this form of the invention, which is somewhat cheaper, due to the absence of the motor, the tube 4 may be connected to a vacuum sweeper of any type which is in general 15 use at the present time, as indicated by the hose coupling 14.

In the operation of the device, the air pump 10 being started or the coupling 14 being applied, the comb is drawn through 20 the hair in the usual way. In this movement of the comb the grooves 2 will collect any dandruff, dirt or the like and, due to the suction created by the pump, the same will be continuously drawn up into the tube 4 25 and thence to the receptacle 11 or the usual receptacle of the vacuum cleaner.

It will be obvious that this device is especially well adapted for use in a barber shop for removing small pieces of hair from 30 the head after the barber has finished cutting the hair. Furthermore, the device is also useful in rinsing soap from the hair after washing. By attaching the hose to a bath tub connection the water will be forced 35 between the teeth of the comb, thereby forming a fan spray of water while being drawn through the hair.

From the foregoing description taken in connection with the accompanying drawings 40 it will be seen that I have provided a comb having simplified means for collecting dandruff and the like; that the means for mounting the comb in the suction-producing apparatus is exceedingly simple, and that 45 the entire apparatus will remove the foreign matter and deposit it in the receptacle provided therefor during the ordinary movements of the comb in combing the hair.

In accordance with the patent statutes, I 50 have described what I now believe to be the best embodiment of the invention, but I do not wish to be understood thereby as limiting myself or the scope of the invention, as many changes and modifications 55 may be made without departing from the spirit of the invention; all such I aim to include in the scope of the appended claims.

What I claim as new and desire to secure by Letters Patent is:

60 1. A comb having a back and a uniform series of corresponding teeth in one integral

solid piece of material, said teeth and back on an outer face thereof having continuous exposed grooves commencing adjacent to the points of the teeth and extending 65 through the upper edge of said back, said grooves at their upper ends being open.

2. A comb as claimed in claim 1, in which said teeth taper downwardly toward their pointed ends and in which said grooves 70 taper downwardly toward their lower ends.

3. A comb having a back and a uniform series of corresponding teeth in one integral solid piece of material, said teeth and back on the front and back outer faces thereof 75 having continuous grooves commencing adjacent to the points of the teeth and extending through the upper edge of said back, said grooves at their upper ends being open.

4. A comb as claimed in claim 3, in which 80 said teeth taper downwardly toward their pointed ends and in which said grooves taper downwardly toward their lower ends.

5. A comb as claimed in claim 1, and a hollow elongated tubular holder therefor, 85 said holder containing a slot through which the back portion of the comb is inserted and said holder and comb having cooperating means for securing the back of the comb within the holder, with the upper edge of 90 said back at about the middle portion of the chamber within the holder, thereby leaving the upper ends of said grooves unobstructed, and said holder having at one end means for the connection of vacuum or other apparatus thereto. 95

6. A comb as claimed in claim 3, and a hollow elongated tubular holder therefor containing in one side a slot to admit the back portion of the comb and having parallel flanges at the sides of the slot to engage the comb, said holder and comb having cooperating means for securing the comb within the holder, with the upper edge of 100 said back at about the middle portion of the chamber within the holder, thereby leaving the upper ends of said grooves unobstructed, and said holder having at one end means for the connection of a vacuum or other apparatus thereto. 105

7. A comb as claimed in claim 3, and a hollow elongated tubular holder therefor containing in one side a slot to admit the back portion of the comb, said holder and comb having cooperating means for securing the comb within the holder with the upper edge of the comb free of the walls thereof, thereby leaving the upper ends of said 110 grooves unobstructed, and said holder having means for the connection of a vacuum or other apparatus thereto. 115

RICHARD M. SMYTHE.
